UNITED STATES PATENT OFFICE.

THOMAS E. BRALEY, OF HORTON, KANSAS.

ROTARY GASOLENE-ENGINE.

943,592.

Specification of Letters Patent.

Patented Dec. 14, 1909.

Application filed June 26, 1909. Serial No. 504,522.

To all whom it may concern:

Be it known that I, THOMAS E. BRALEY, a citizen of the United States, residing at Horton, in the county of Brown and State of Kansas, have invented certain new and useful Improvements in Rotary Gasolene-Engines, of which the following is a specification.

This invention relates to gasolene engines, and more particularly to an engine in which at each reciprocation of a piston member a fresh explosive impetus is given to the device.

A most important object of the device is to provide a novel form of piston and system of gas intake whereby compressed gas may be supplied to the explosion chamber at each reciprocation of the piston.

A further important object is to provide a novel form of casing.

Other objects and advantages will be apparent from the following description, and it will be understood that changes in the specific structure shown and described may be made within the scope of the claims without departing from the spirit of the invention.

In the drawings forming a portion of this specification, and in which like characters of reference indicate similar parts in the several views, Figure 1 is a vertical cross sectional view of the device, the arrows indicating the direction of movement of gas prior to explosion, Fig. 2 is a cross section at right angles to Fig. 1, Fig. 3 is a perspective view of one of the piston shoes, Fig. 4 is a detail of one of the piston and compression members, Fig. 5 is a side view of the rotor with the piston removed.

Referring to the drawings, there is shown a casing 10 the interior surface of which is in the form of an oval orbit, and is provided with a spark plug 11 and an exhaust port 12 on opposite sides at its lesser dimension. Mounted revolvably within the casing nearer one end than the other, there is a rotor 13 approximately cylindrical in shape and provided with a central circular enlargement 14 having a lateral extension 15 communicating with an annular inlet passage 16 formed on the inner face of the casing and communicating with the supply pipes 17.

The surface of the piston is provided with opposite peripherally extending recesses 18, at one end of which there is formed an en-

larged cylindrical socket portion 19 communicating with the recesses at one side and receiving pivotally therein the enlarged trunnion portion 20 of a vane. The trunnion is provided in its outer face with grooves 22 in which are slidably disposed packing rings 23 having suitable springs 24 disposed inwardly thereof to hold them in close contact with the inner face of the pivot 65 socket.

Extending radially through the center of the rotor there is an intake passage 25 having at its outer extremities spring pressed valves 26 arranged to yield to outward passage of gas therethrough and adapted to close tightly against inward pressure. The passage 25 communicates centrally with each of the recesses 18 as will be observed. It should be noted that the vanes 21 extend the full width of the casing, and are provided with longitudinally extending grooves 27 in their edges in which are disposed packing bars 28 pressed into close contact with the side walls of the casing by means of suitable springs not shown. Opening from the recess 18 between the intakes 25 and the pivoted end of the vane 21, there is a conducting passage 29, opening adjacent the opposite recess 19 outwardly of the proximal vane. This passage is provided at its outer end with a valve adapted to yield to outward pressure of gas from within, and to close tightly against pressure from without.

Opening inwardly from the end of the recess 18 opposite the socket 19, there is an arcuate compression chamber 31, extending the full width of the rotor, the arc thereof having as its center the axis of the pivot socket 19, the inner end of this chamber 90 communicating with the passage 25 as shown at 32. Engaged slidably in the chamber 31, there is a piston member 35 similar in form to the vanes 21, formed integral therewith and similarly provided with side compression bars 36 forming a continuation of those 28 and being similar except that the inner ends of these have cross portions 37. Formed in opposite sides of the chamber 31 adjacent its outer end, there are a series of grooves having packing bars 39 disposed therein and pressed resiliently against the piston by means of springs 24. At the junction of the piston 35 and of the vane 40, similar to that 21 and pivotally engaged therein, there is a shoe block 45, having a

- trunnion engaged with the socket. The outer face of the block 45 is curved, and adapted to engage closely against the peripheral face of the casing 10. Carried in 5 a suitable recess 47 opening from the recess 18 adjacent the pivot socket 19, there is a spring 48 bearing against the inner face of the vane 21 to initiate its outward movement if necessary, upon the explosion side of 10 the chamber.

The operation of the device will be readily understood, the outward movement of the vanes 21 into the explosion space B drawing a charge of gas through the passages 25 and 15 into the space under the vane and into the compression chamber 31, from whence it is expelled and compressed in the passages 29 as the vanes are pressed inwardly upon reaching the compression side of the chamber A. Thus a fresh charge of gas is introduced in the explosion chamber each time 20 the vanes pass the spark plug 11, and the spark being properly timed, an impetus is given the rotor on each rotation of each 25 vane.

It will be understood that any suitable connection of the usual type may be made between the shaft of the rotor, a timing mechanism, electrical source and the spark 30 plug, which it is not deemed necessary to illustrate.

It will be noted that the exhaust passage extends some distance peripherally through 35 the walls of the casing, in order to allow exhaustion of burned gases more readily.

It will be readily appreciated that the passage of the freshly vaporized gasolene through the rotor as described will serve largely to cool the rotor, vanes and piston, 40 thus obviating the dangers of overheating the rotor which constitutes one of the principal difficulties in the operation of rotary gas engines.

What is claimed is:

- 45 1. A rotary gas engine comprising a casing having curved walls, a rotor mounted eccentrically of the casing, an igniting means carried by the casing, said casing having an exhaust port spaced from the igniting 50 means, reciprocating members carried by the

rotor adapted to create a vacuum spaced inwardly thereof upon operation, said rotor having gas intake passages therethrough opening under the reciprocating members, said rotor having also outlet passages opening at one end inwardly of the reciprocating members, and at the other end intermediate of the reciprocating members; valves disposed in the intake passages to prevent escape of gas therethrough, and valves disposed in the outlet passages to prevent ingress of gas therethrough; said reciprocating members being constructed and adapted to draw in gas from said inlet passage upon movement in one direction and to compress and expel the gas through said outlet passage upon reverse movement.

2. A device of the class described comprising a casing having curvate inner walls, and having igniting means at one side and 70 having an exhaust port spaced therefrom, a rotor mounted eccentrically within the casing, vanes pivoted upon the rotor, said rotor having curved compression chambers formed in an arc centered on the pivotal 75 points of the vanes, slideable piston members carried in said chambers and pivotally connected with the outer ends of the vanes, said vanes and pistons being adapted to form an airtight chamber inwardly thereof when the vane is spaced outwardly of the rotor, gas inlet passages communicating with the compression chamber and spaced inwardly of the vanes, an opening through the side of the rotor, a gas inlet passage formed in the 80 casing and communicating with the inlet passage in the rotor and a conducting passage communicating with the space inwardly of the vanes and opening outwardly of and adjacent the pivoted end of another 85 vane, and check valves in said inlet and conducting passages constructed and arranged to check pressure from the direction of the explosion space.

In testimony whereof I affix my signature, 95 in presence of two witnesses.

THOMAS E. BRALEY.
